UNITED STATES PATENT OFFICE

BENJAMIN W. FREEMAN, OF CINCINNATI, OHIO

SHANK BEATING AND STITCH RUBBING MACHINE

Application filed October 11, 1927. Serial No. 225,536.

My invention relates to machines for beating down shoe shanks and the foreparts, particularly in welt shoes, where a close edge is desired. The invention also relates to machines for rubbing down the stitches, particularly in welt shoes, before the tread channel flaps are closed.

In the art there have been a number of different types of machines for this type of work, but with the development of present styles, particularly in welt shoes, the machines referred to do not seem entirely suitable. In the manufacture of welt shoes it is customary to form a thin channel flap on the tread surface of the outsole close to the outer edge, and after the stitching operation which secures the outsole to the welt is completed, this flap is closed down to conceal the stitches.

20 I propose to guide by combining with the shank breaking tool an independent guide which may be moved along the root or outer base of the tread channel flap. Ordinarily an angular shoulder is formed between the 25 flap and the channel, and it is the object of my invention to provide a guiding device which will function along this shoulder. As the beating iron may extend the full width of the channeled edge at its widest point, 30 it will merely protrude over the edge in narrower portions without causing damage.

I further have, as an object, the combination with the beating tool and the guide of a guard which will insure protection to the 35 shoe if the operator should, during the operation, allow the shoe to run out of alignment with the guiding device. It is my object to provide a guard or guards on the sides of a breaking tool and to also provide a guide 40 which, when the operator holds the shoe with the main body of the shoe sole extending either inwardly or outwardly from underneath the breaking iron, will positively protect the shoe or sole on the sides of the beating tool.

It is further my object to so mount the guide that it will give with pressure of the shoe bottom against the tool, and which also 50 may be adjusted so that the operator can car-

ry out the beating operation holding the shoe at a desired angle.

The above and other objects to which reference will be made during the ensuing disclosure I accomplish by that certain combination and arrangement of parts of which I have shown a preferred embodiment.

In the drawings:—

Figure 1 is a side elevation of the head of my improved shank breaking and stitch rubbing machine.

Figure 2 is an end elevation of the head shown in Figure 1.

Figure 3 is a perspective view of the beating tool or iron.

Figure 4 is a sectional view as it would appear taken along the lines 4—4 in Figure 2, with the position of a shoe being operated upon also indicated in section.

Figure 5 is an end elevation of the breaking iron.

Figure 6 is a side elevation of an improved type of breaking iron with the outside face having the same curve as the finished surface of the channel.

The machine is usually mounted on a standard or base on which either a driving pulley or a motor is set. These parts are not illustrated as they form no part of my invention. I have indicated at 11 a tubular pedestal in which the head 12 of the machine is adjustably mounted. On the head of the machine there are a pair of journal boxes 13, 14, which journal the shaft 15 which carries the beating iron. The shaft 15 is operated by a belt 16 which passes about a pulley 17 which is secured on the shaft. The end of the shaft opposite that on which the pulley 17 is mounted is tapered and recessed as indicated. On the tapered end of the shaft in an annular channeled portion 19 I have shown the freely mounted sleeve 20, which is of such diameter as to provide clearance for the channel flap. The beating tool generally indicated at 21 has a recessed end 22 which is engaged by the head of a screw 23 threaded in the end of the shaft 15. In the modified type shown in Figure 6 we have indicated a tool having a beating surface contoured to the shape of the finished channel. Interspacing the sleeve 20

95

100

and the beating iron 21 I have shown my novel guide which consists of a thin plate 24 extending slightly beyond the outer extremities of the beating tool. The plate 24 has a central opening which clears the shaft 15, thereby allowing resilient movement of the plate. For supporting the plate I have shown an arm 25 mounted on a boss 26 on an adjustable auxiliary bearing member 27. The arm 25 is preferably formed integrally with the plate 24.

As a guard to prevent damage by the tool because of the shoe slipping out from under the tool I have shown in addition to the guarding sleeve 20, the guard 28 which is countersunk as indicated at 29 and clears the inner surface of the head of the screw 23, thereby permitting the guard to be carried in a freely rotatable position in a portion 21a of the beating iron 21 which has a reduced diameter. The outer periphery of the guard 28 is of such dimension as to lie substantially in alignment with the outer extremities of the beating iron, although it may be smaller or larger. The inner edge of the guard may, in some instances, be used in combination with the guiding device hereinbefore described.

The beating iron, which is not new, except in the modified form shown in Figure 6, has outer extremities 29 against which the channeled portion is pounded, and recessed portions 30 which make the device function with the same effect as repeating blows of a hammer.

Referring to Figures 4 and 6, it will be observed that the projections 29 of the tool which accomplish the pounding, rubbing, and beating action, are of concave shape so that in the application of the tool to the channel of a sole, the channel will be beaten and rubbed in a convex plane. With the old type of flat surfaced beater it was necessary to vary the angle at which the shoe channel was applied to the tool beginning in a plane parallel with the flat surface of the tool, and then inclining the shoe to cause the outer edge of the channel to lie down snugly against the upper. With my new curved surfaced tool, full pressure of the full width of the channel may immediately be applied to the tool. The time required for the operation is materially reduced. The guiding is also a simpler matter, as the tool gets more of a purchase in the channel. Another advantage is that the beating action with a tool having a non-flat surface causes less of a burnishing and glazing action on the channel, and the upper surface of the channel has more of a sanded effect which makes a tighter bond with the cement with which the flap is applied to the channel.

In use the shoe is held in the position indicated in Figure 4, the thin lower edge 31 of the plate 24 being guided against the angular

shoulder formed by channel flap. By turning the shoe in a clockwise direction, as indicated in Figure 4, and bearing up against the tool, the channeled edge is beaten over so as to close the gap between the upper surface of the welt and the outer surface of the upper. In breaking the channeled edge of the shank and the channeled portion of the tread of the sole the operator usually starts in close to the heel and bears upwardly with the shoe while he advances the channeled edge along with the thin edge 31 of the guide passing along against the angular shoulder of the channel flap. When the operator has reached the tip of the sole he turns the shoe around in his hands and beats down the other edge of the sole in a similar manner.

The guard 28 prevents the shoe from coming in contact with the rotating beating iron in case the shoe should slip from the position in which it is held against the beating iron.

If the shoe should slip in the other direction, no harm will result as all that will happen in this contingency will be for the shoe to rub against the freely mounted sleeve 20.

Modifications in structure will readily occur to those skilled in the art in which the support for the guide and the particular journal support and mechanical correlation of parts is varied, but in so far as machines are built which guide by means of the angular shoulder formed by the channel flap, I consider such modifications within the scope of my invention.

Having thus described my invention, what I claim as new and desire to secure by Letters Patent, is:

1. In a shoe shank beating and stitch rubbing machine a rotatable shaft having a beating tool mounted adjacent its end and an independent adjustable guide for work mounted adjacent the inner edge of said tool, said guide having an edge adapted to be guided along the angular shoulder of a channel flap at its juncture with the sole of a shoe.

2. In a shoe shank beating and stitch rubbing machine the combination with a beating tool of a guide for work, said guide having an edge adapted to be guided along the angular shoulder of a channel flap at its juncture with the sole of a shoe, said guide being aligned with the inner edge of the beating tool, said guide being resiliently mounted whereby various positions of a shoe with relation to the beating tool may be achieved with the edge of the guide remaining in the line of the angular shoulder.

3. In combination with a beating iron, means independent of the iron aligned with the inner edge thereof for guiding a shoe bottom so that a channeled portion thereof will engage said beating iron, said means movable with reference to the shoe bottom

- along a line interspaced from the edge of the sole of the shoe.
4. A shoe shank beating and stitch rubbing machine having a beating iron, and a guide for controlling the position of a shoe bottom pressed against said beating iron, said guide aligned with the inner edge of the iron and movable with relation to said shoe bottom along a line interspaced from the edge of the shoe sole and a guard freely mounted adjacent the opposite edge of said iron.
5. A shoe shank beating and stitch rubbing machine having a beating iron, and a guide for controlling the position of a shoe bottom pressed against said beating iron, said guide movable with relation to said shoe bottom along a line interspaced from the edge of the shoe sole, said guide being mounted independently of said beating iron adjacent the inner edge thereof.
6. A shoe shank beating and stitch rubbing machine having a beating iron having concave beating portions, and a guide for controlling the position of a shoe bottom pressed against said beating iron, said guide movable with relation to said shoe bottom along a line interspaced from the edge of the shoe sole, said guide being mounted independently of said beating iron, said guide being resiliently mounted so as to yield to pressure of the shoe bottom against said beating iron.
7. A shoe shank beating and stitch rubbing machine having a beating iron, an independent guide for a shoe bottom being beaten against which a line interspaced from the edge of the shoe sole may be pressed, and a guard for preventing damage to the shoe, said guide being mounted independently of said beating iron, and said guard being carried on the side of the beating iron opposite to the side on which said guide is mounted.
8. In a machine of the character specified, beating means, and yieldably mounted channel flap guiding means mounted independently of said beating means adjacent its inner edge.
9. In a shank beating and stitch rubbing machine the combination of a beating iron, a guard disposed adjacent the beating iron on one side thereof, and a guide for the work disposed on the other side of the beating iron, said guide having an end shaped to fit within the groove at the root of the channel flap.
10. In a machine of the character specified, rotary beating means, guiding means, and guarding means on both sides of said beating means, said guarding means being located on opposite sides of the axial portion of the beating means.
11. In a machine of the character specified, rotary beating means, guiding means, and guarding means on both sides of said beating means, and said guarding means being loosely mounted with relation to said beating
- means, said guarding means being located on opposite sides of the axial portion of the beating means.
12. A shank beating and stitch rubbing tool having beating portions of concave shape conforming to the convex plane of a beaten shoe sole channel, and means for preventing said tool from engaging the channel flap.
13. A shank beating and stitch rubbing tool having curved beating portions substantially complementary to the shape of a beaten shoe sole channel, and means for preventing said tool from engaging the channel flap.
14. In a shoe shank beating and stitch rubbing machine, a rotatable shaft having a beating tool mounted adjacent its end and a guide for work, said guide having an edge adapted to be guided along the angular shoulder of a channel flap at its juncture with the sole of a shoe, said guide being adjustable to various angles of inclination and being mounted adjacent the inner edge of the tool.
15. A shoe shank beating and stitch rubbing machine having a beating iron, and a guide for controlling the position of a shoe bottom pressed against said beating iron, said guide movable with relation to said shoe bottom along a line interspaced from the edge of the shoe sole, said guide being mounted independently adjacent the inner edge of said beating iron, and being adjustable to various angular positions.
16. A rotary tool for beating the channeled margin of a shoe sole after the leaf has been turned back and the sole stitched to the remainder of the shoe, said tool having beating portions of a width sufficient to beat the channel parts only and of a shape concave corresponding to the convex shape desired for the finished beaten channel for the purpose described.
17. A rotary tool for beating the channeled margin of a shoe sole after the leaf has been turned back and the sole stitched to the remainder of the shoe, said tool having circumferentially arranged projections constituting beating portions of a width sufficient to beat the channel parts only and of a shape concave corresponding to the convex shape desired for the finished beaten channel for the purpose described.
18. In a shank beating and stitch rubbing machine, a rotary shaft, a beating tool on said shaft and a guide, said guide having a relatively thin plate portion extending radially of the tool axis and in close juxtaposition with the lateral face of the tool, the outer end of said plate portion constructed to extend between the channel flap and the beating face of the tool, and arranged for entering and engaging along the angular shoulder of the channel flap at its juncture with the shoe sole.
19. In a shank beating and stitch rubbing machine, a beating tool, means for actuating

it for beating across the entire exposed channel of the outsole of a shoe, a guide, said guide having a relatively thin plate portion extending along the lateral or non-working face of the tool at substantially a right angle to its working surface and constructed to extend between the channel flap and the beating face of the tool, and arranged to enter and engage along the angular shoulder of the channel flap at its juncture with the shoe sole.
